MACHINE FOR STRAIGHTENING AND
TRUING WHEELS

John Fried, Peoria, Ill.

Application June 5, 1939, Serial No. 277,370

3 Claims. (Cl. 153—48)

This invention pertains to machines for straightening and truing metal automobile wheels.

An object is to furnish a mechanism simple in construction and operation, thoroughly efficient, and that can be made to perform service on a given piece of work in a comparatively short time as compared with known devices.

Another object is to provide a mechanism that in one operation will quickly restore a badly deformed wheel and wheel-rim to approximately normal condition and in a succeeding operation complete the final truing of the whole.

Again, an object is to provide a machine upon which a deformed wheel may be permanently mounted in one position during operation thereon and which by manipulation of the machine parts thereon may be restored to running condition in a minimum of time.

Still another object is to provide a mechanism upon which a deformed wheel may be permanently mounted at and by its central portion during complete straightening and truing operations and so held that upon being replaced on the vehicle will be wholly true.

That the invention may be thoroughly understood the appended drawings are provided forming part hereof, wherein:

Figure 1 is a sectional elevation of a machine illustrating the invention;

Figure 2 is a plan of the same as produced on line 2—2 of Figure 1;

Figures 3 and 4 are respectively a side elevation, and a transverse section of a hook member shown in the previous figure;

Figures 5 and 6 are sectional views of a distributor valve shown in two different positions;

Figure 7 is an enlarged elevation of a pump shown in Figure 1;

Figure 8 is an elevation of part of the machine shown in the earlier figures illustrating one manner of operating upon a wheel, and

Figures 9 and 10 are views somewhat similar to Figure 8 showing another manner of operation.

In Figure 1, the character 1 designates in this instance a cylinder erected on a suitable base 2, a series of arms 3 carried by said cylinder supporting a table 4 having an opening 5 central thereof. A piston 6 operates within the cylinder and is provided with any usual packing 8 to preserve fluid tight action. One end of the cylinder is closed by a cap 9 and a suitable packing at 10, while a packing is likewise provided at its other end at 11, the said piston being adapted to enter the base 2 as a guide therefor, and likewise ex-

tends through the opening 5 of the table 4 and supports a plate 12 whose top surface is exactly parallel to the table's top, said plate receiving upon it the usual flat center portion of the wheel A to be operated upon.

The piston has a threaded bore 13 in its upper end to receive a cap screw 14 beneath whose head is a plate 15 which may clamp the wheel A between itself and said plate 12.

10 Means is provided for moving the piston in either direction. While such means may be of any form suitable to put forth great power, a hydraulic type is preferred. That is to say, at 16 is a tank for holding a supply of oil. Said tank is connected through a pipe 17 with a distributor-valve 18, Figures 5 and 6, the casing 18' of said valve being connected into a pipe 19 which is connected in the lower part of the cylinder 1, or below the piston 6. Said casing 18' is also connected with the upper end of the cylinder through a pipe 20, being also connected by a pipe 21 extending into the said tank 16.

The pipe 17 has therein two check valves 22 of well known type and connected in said pipe 25 between the valves is a pipe 23 extending from a hand pump 24 for example, Figure 7.

It is to be noted that by rotating the valve 18 the pipes 17 and 19 will be placed in communication, Figure 5, as will the pipes 20 and 21, wherefore 30 as in Figure 6 the pipes 17 and 20 will communicate as will the pipes 19 and 21. By this type of connection the pump in action will withdraw oil from the tank 16 through a check valve 22 and force it to the lower part of the cylinder 1 through the pipe 19, the second check valve, of course, preventing return of oil toward said pump. The piston 6 during this time will be raised and the oil above it will flow through the pipe 20, valve 18, and pipe 21 to the tank. On the other hand 40 if the valve 18 has the position shown in Figure 6 the oil still drawn from the tank 16 will flow under pump pressure through pipes 17 and 20 to the top of the cylinder, the return of oil from the lower portion of the latter to the tank 45 through pipe 19 valve 18 and pipe 21.

It is seen that great operating pressure is at hand in operating upon work requiring extreme pressure. In addition to the parts thus far described a series of arms 25 are spaced around the 50 outer edge of the table 4, being pivoted thereto in substantially the manner and in the position shown. The arms are provided each with a hooked free end 26 extending in the direction of the center of the table. Their lower ends are 55 pivoted between brackets 27 on bolts 28, for ex-

ample, said bolts being much smaller in diameter than the holes in the said brackets whereby the arms may freely about the under side of the table so that heavy strains may be imposed on the arms without respect to said bolts. Preferably the arms snugly fit between their brackets so that friction will hold said arms in any position placed.

The structure having been made known, the manner of straightening and truing wheels by the same can now be described.

The all metal wheels as now generally used are distorted into all manner of conditions as is known. However, due to the fact that the central portion of the wheel is rigidly bolted to a hub or to a brake drum of a vehicle such portion can be distorted but little, if any. This central portion is that by which the wheel is carried by the machine herein, or, more specifically, by the plate 12 whose wheel receiving top surface parallels the top surface of the table 4.

As shown in the drawings the wheel-center is clamped between the said plate 12 and plate 15 by the cap-screw 14 where it may be held securely and permanently during all truing operations, it being clear that the wheel may be raised and lowered by any action given the piston 6 by the pump 24.

The wheel shown in Figure 1 is shown as brought to a quite true form after operations thereon now to be made clear, while Figure 8 illustrates a mounted wheel that has been considerably distorted, the portion lowermost therein being in substantially its normal position with respect to the central portion thereof. When so mounted the hooked arms 25, in this particular instance, may be raised to the position shown with their hooked ends 26 lying in such positions as to be in the path of the extreme outer portion of the wheel-rim. It is noted that the wheel body and said wheel-rim in this instance are much twisted and that opposite portions of the rim lie at different heights. Now by causing the piston to be elevated, as here considered, the highest portion of the rim will first engage a hook or hooks, as the case may be, the continued piston-action finally carrying the lowest portion or portions of the rim beneath the remaining hooks.

The arms 25 are, of course, of equal length between the table 4 and the hook ends 26 so that they lie in and define a plane paralleling the center portion of the wheel as it lies between the plates 12 and 15. Therefore when the said center portion has been raised to a position where the rim lies as nearly as possible in one plane the wheel as a whole has been brought quite closely to normal form, or as shown in the other figures of the drawings.

Having thus operated upon the wheel the arms 25 may be swung out of the way beneath the table, for example. Following this the wheel is lowered by piston-action until its rim meets the table 4 at which time the operator may observe at what point or points the said rim is out of true or lies in spaced relation to the table's surface. Figures 9 and 10 represent an exaggerated example, perhaps, of such a condition or where the operation previously described has provided the initial straightening.

Having noted the "high point" of the rim with respect to the table the piston is made to raise the plates 12, 15 to lift the rim from said table a sufficient distance to permit the insertion of a wedge B for example, Figures 2 and 10, beneath the "low" side of the rim, the operator judging

from experience the probable thickness of wedge to be inserted to bring about the desired truing, whereupon the plates 12, 15 are lowered, the extreme power available then forcing the "high point" toward the table, or even upon it, to strain the wheel or its rim, or both, to the position, finally, where the plane of rim rotation exactly parallels the plane of rotation of the wheel's firmly clamped center portion, this being determined from time to time after removal of the wedge.

It is observed that the wheel once mounted on the plate 12 need not be removed during these operations and thus a saving of much time and unnecessary manipulations are avoided, the wheel being exactly trued before being removed in finished condition.

It is possible, also, to straighten the wheel by another method by the mechanism illustrated. That is to say, the wheel shown deformed as in Figure 8 may be reversed in position with the "high" portion extending toward the table. In this placing of the wheel the descent of the piston will carry said high portion first upon the table following by the other parts of the rim, the whole then appearing again as in Figure 9, the already described final truing of the rim being thus brought about. Either method is open for use though that first described may be preferred as leading to more expeditious handling of the work. Or, again, the wheel as originally mounted between the plates 12, 15 may be lowered by the piston upon the wedge B to bring about the final truing, or it may be raised to engage one or more of the hook-ends or abutments to the same end, depending upon the required direction of strain to be imposed, the amount of springing back of the work, in any event, being naturally considered in such operations by carrying the straining action slightly beyond the judged true limit. In respect to the final truing of the rim it is understood that according to conditions existing during operations the wedge B is shifted to a variety of positions always at a "low" point so that a "high" point existing can be drawn down to finally obtain the required truing, a hook-end or abutment answering also for such purpose.

Emphasis must be placed upon the fact that heretofore but one or two hook members or abutments have been used to bring about a final alignment of a wheel-rim, such method requiring the rotation of the wheel by hand to bring a given rim-portion in position to be operated upon. As distinguished therefrom the present apparatus employs a considerable number of fairly closely spaced abutments by the use of which the entire rim is engaged at one operation (see Figure 8 of the drawings) thereby more quickly bringing about the reforming of the wheel in the initial truing at all points. But a single operation is required, therefore, by this distinction, since no continued trials and lengthy manipulations are necessary for the final result, coupled with the fact that, as in the older methods no one region can be unduly strained beyond an ideal position which afterward must be operated upon in an opposite direction for correction purposes. Again, the series of arms 25 since arranged entirely around the table 4 may receive such portions of the rim as may be required to be brought into shape all parts being strained alike in the single operation. And by means of the structure employed the wheel may be clamped in position on the piston without

respect to which side is uppermost and may be either brought upon the arms 25 or upon the table 4 in the reforming act.

The downwardly extending hooks 26 are so presented to the work that they abut upon a firm practically distortionless part of the rim inward from the easily bent rim-edge. The latter, therefore, cannot be damaged or caused to lose its proper smooth appearance.

As has been intimated, the central mounting of the wheel upon a support such as the plate 12 whose working surface parallels the table top makes for exact truing where the wheel-rim is made to exactly abut the latter in the final operations herein set forth.

In one or more of the claims the term "abutment" will be used in referring to the hook-carrying arms 25 in the interest of brevity. Naturally, of course, an abutment serving the purpose of said arms may be other than a series of the latter.

It will be apparent that the overhanging extensions or hooked end portions 26 of the arms 25 present a series of work engaging points which extend concentrically around the center line of the plate 12 which, together with the plate 15, comprises the work holding means, and that all of the work engaging points are not on one side of a line drawn diametrically through the center line of the work holding means, but the series extends through an angle of greater than 180° concentrically around the center line of the work holding means. For example, as shown in Fig. 2, the arms 25 and their overhanging extensions 26 are spaced apart substantially equally circumferentially with respect to the center point of the work holding means.

I claim:

1. A machine for straightening and truing deformed wheels comprising a supporting structure including a substantially circular table, a work-carrying member at the center of said table and shiftable with respect to said table in a direction at right angles to the plane of said table, parts carried by the work-carrying member by which to clamp the center portion of a wheel to be operated upon, and a plurality of supported abutment means spaced from each other and positioned around said table and spaced from said table in and defining a plane parallel to the top of said table, each of said abutment means having one end pivotally mounted beneath the lower face of said table for adjust-

ment in a vertical plane extending radially with respect to said work-carrying member and the other end overhanging said table and points along the circumference of a wheel rim on the side thereof in the clamped position of the wheel, the said plurality of abutment means defining a plane limiting the upward movement of said work-carrying member and a wheel carried thereupon and receiving said side of the wheel rim in abutment thereagainst in the upward travel of said work-carrying member.

2. A machine for straightening and truing deformed wheels comprising a base, a column, a table having a central opening located in concentric relation to said column and supported in stationary concentric relation to the column by means extending outwardly from said column, arms at least three in number equidistant from the center of said column and secured at 15 fixed points to said table and extending upwardly, an extension projecting from each arm laterally over said table and constituting abutment means, the abutment means on said arms defining a plane parallel to the table, work carrying means arranged centrally of said table, and power operated means for raising and lowering said work carrying means to force the work against either said abutment means or said table, said power operating means being supported by 20 said column and extending through the central opening in said table.

3. A machine for straightening and truing deformed wheels comprising a base, a column, a table having a central opening supported in stationary concentric relation to the column by means extending outwardly from said column, work carrying means arranged centrally of said table, a plurality of arms secured to said table and extending upwardly, an extension projecting laterally from each arm and overhanging said table, the under surfaces of said overhanging extensions defining a plane parallel to said table and presenting a series of work engaging points which extend concentrically around the center line of the work holding means through 35 an angle of greater than 180°, and power operated means supported by said column for causing relative movement between said work carrying means and said table and arms to effect a 40 forceful contact between the table and the work or between the work and the under surfaces of the extensions on said arms.

JOHN FRIED.
